UNITED STATES PATENT OFFICE.

WALTER H. KNIGHT, OF NEW BRIGHTON, NEW YORK.

CONTROLLER FOR FLUID-PRESSURE MOTORS.

SPECIFICATION forming part of Letters Patent No. 586,605, dated July 20, 1897.

Application filed June 3, 1896. Serial No. 594,084. (No model.)

To all whom it may concern:

Be it known that I, WALTER H. KNIGHT, a citizen of the United States, residing at New Brighton, in the county of Richmond and State of New York, have invented certain new and useful Improvements in Controllers for Fluid-Pressure Motors, of which the following is a specification.

The main object of my invention is to provide means for placing all of the valves and operating devices of a fluid-pressure motor under the control of a single controlling device.

Another object of my invention is to provide the motor-cylinder with automatic vacuum-relief valves which will automatically admit air to the cylinder after the cut-off of the fluid to prevent formation of a partial vacuum behind the piston. These automatic relief-valves are also controlled by a single controlling device, so as to be automatically opened when the fluid-pressure has been cut off to enable the motor to run freely for facilitating coasting, my improved fluid-pressure engine being particularly adapted for motor-cars. To accomplish these objects, I provide an automatic vacuum-relief valve at each end of the motor-cylinder. Suitable connecting devices extend from the valves to the controlling device, whereby they can be simultaneously opened by a movement of the controller. I provide the steam-distributing valve of the motor with any suitable reversing mechanism, which is also connected to the controlling device, and for supplying the compressed air I provide an air-reservoir and a reducing-valve, a high-pressure throttle-valve being interposed between the reservoir and reducing-valve and a low-pressure valve being interposed between the reducing-valve and fluid-chest of the motor. Both the high-pressure and low-pressure throttle-valves are connected to the controlling-valves to be simultaneously opened or closed thereby. I prefer to include a heater in the system between the reducing-valve and low-pressure throttle-valve.

In order that my invention may be fully understood, I will first describe the same with

reference to the accompanying drawings and 50 afterward point out the novelty with more particularity in the annexed claims.

In Figure 1 of said drawings I have represented my invention in diagrammatic sectional elevation, and in Fig. 2 a sectional view 55 of the relief-valve.

A is the engine-cylinder, in which operates the piston B, mounted on the piston-rod C, which is connected to the sliding cross-head D.

E is the crank-shaft, carrying the crank E', which is connected to the cross-head D by the pitman F.

G is the fluid-pressure chest, communicating with the opposite ends of the cylinder A, 65 and G' is the distributing sliding valve.

H is an ordinary reversing-link suitably connected to the distributing-valve G' and adapted to be operated by the eccentrics I on the crank-shaft E.

J is a compressed-air reservoir, and J' is a high-pressure throttle-valve located in the supply-pipe extending from said reservoir.

K is a reducing-valve, and L is a heater interposed in the fluid-pressure-supply pipe between the high-pressure throttle-valve and engine.

M is a low-pressure throttle-valve located between the heater and engine. The throttle-valves J' and M are suitably connected by 80 toggle-links N, by reason of which they are simultaneously opened or closed.

O is the longitudinally-movable controlling-rod, sliding in bearings O'. The rod O is pivoted to the knuckle of toggle-links N.

P is the controller-lever, connected through link P' and bell-crank lever P² with the longitudinally-movable controller-rod O.

H' is a bell-crank lever, and H² is a connecting-rod which connects the reversing-link 90 H with the controlling-rod O.

In the opposite ends of the cylinder A are automatic vacuum-relief valves Q. (Shown in the enlarged detail sectional view.)

Q' are bell-crank levers engaging the valve-stems of the relief-valves Q and formed with lugs q on their short arms, which are adapted to be engaged by cam-shoulders R on the con-

troller-rod O. By these means the valves Q are forced open and held open by the controlling mechanism when the throttle is closed, so as to prevent the excessive compression 5 that occurs when the link is at mid-gear, the air as it is compressed passing through the valves Q and into the crank-basin or else around to the other end of the cylinder through by-pass T. When the throttle is open and 10 the motor doing work, the valves Q act as ordinary vacuum - relief valves, opening inwardly whenever the pressure in the cylinder falls below the atmosphere. In any case whether acting as vacuum - relief valves or 15 compression-relief valves the arrangement is such that only pure air free from dust will be admitted to the cylinder from the crank-chamber.

The engine is shown at rest with the reversing mechanism in central position, the relief-valves open, and the high and low pressure throttle - valves closed. It will be observed that by moving the hand-lever P in either direction both throttle-valves will be 20 opened, while the reversing-link will be moved either upward or downward, and the cylinder-relief valves will be simultaneously allowed to close.

While I have shown mechanism for utilizing 25 the vacuum-relief valves as compression-relief valves, I may provide separate valves for this purpose, in which case the compression-relief could take the form of a stop-cock or valve placed in a by-pass between the two 30 ends of the cylinder, the controller opening such cock or valve when it closes the throttle, and vice versa. Such a modification is indicated by dotted lines in the drawings, U being a passage communicating between the 35 ends of the cylinder and V a cock in said passage provided with a crank-arm V', connected to controlling-rod O by link W. This form of relief-valve in a by-pass communicating between the ends of the cylinder is described 40 and claimed in my application, Serial No. 597,328, filed June 29, 1896, for improvements in motor-vehicles. I have found that the use 45 of such compression - relief valves not only enables the motor to "run free" or without power for a much longer time than when they 50 are not used, but also conduces greatly to the smoothness of operation. In air-motors this feature of relieving compression when the motor is running free is especially necessary on 55 account of the fact that the air differs from steam in not condensing. It is particularly valuable in the case of vehicles, where about half the time the motor is coasting, as otherwise if the compression is not relieved there 60 is a very decided retardation. Of course a large part of the energy of compression is returned into mechanical work by subsequent expansion on the back stroke; but owing to the fact that the air is heated to a high degree by compression and some of the heat es-

65 capes by radiation there is always a loss by the variation of the energy of compression, amounting to probably about twenty per cent.

Having thus described my invention, what I claim as new, and desire to secure by Letters Patent, is—

1. The combination in an air-motor, of a throttle-valve, or other means of controlling the power of the motor, vacuum-relief valves opening inwardly to relieve the cylinder of 70 vacuum, and mechanism for holding open said vacuum-valves, said mechanism being connected with the motor-controlling mechanism so that the said vacuum-valves will be held open when the motor is not doing work, in 75 order to relieve the motor of compression occurring at the ends of the stroke.

2. The combination in an air-motor, of vacuum-relief valves, and means for holding the same open when the motor is not doing work, 80 of a passage or passages communicating with both valves and also with the crank-basin or exhaust-chamber of the motor so that nothing but pure air will be drawn into the cylinder.

3. A controller for air-motor vehicles constructed to operate the high-pressure throttle leading from the high-pressure reservoirs, the low-pressure throttle, the variable cut-off, and reversing mechanism, and the compression-relief valves, with one handle, the off position 90 of the handle closing both throttles and opening the relief-valves.

4. The combination of a fluid-pressure engine, provided with a compression - relief valve, with a high-pressure reservoir, a throttle-valve and a controlling device adapted to 100 simultaneously operate the relief-valves and throttle-valve, substantially as set forth.

5. The combination of a fluid-pressure engine, provided with compression-relief valves 105 and a fluid-distributing valve, suitable reversing mechanism, a fluid-pressure reservoir, a throttle-valve, and controlling means adapted to simultaneously operate the relief-valves, the reversing mechanism and the throttle- 110 valve, substantially as set forth.

6. The combination of a fluid-pressure engine having suitable compression - relief valves and a fluid-distributing valve, suitable reversing mechanism, a compressed-air reservoir, a high-pressure throttle-valve, a reducing-valve, a low-pressure throttle-valve, and suitable controlling means adapted to simultaneously operate the cylinder-relief valves, the reversing mechanism and the two throttle-valves, substantially as set forth.

7. The combination of a fluid-pressure engine, provided with automatic vacuum-relief valves and a fluid-distributing valve, with a throttle - valve, and a controlling device 125 adapted to open the relief-valves when the throttle-valve is closed and vice versa, substantially as set forth.

8. The combination in a fluid-pressure motor for motor-vehicles, of a motor-cylinder 130

having compression-relief valves, with a motor-controlling device regulating the supply of fluid to the cylinder and operatively connected with the compression-relief valves, said controlling device being adapted to simultaneously operate said relief-valves to hold them open when the motor is not doing

work, in order to relieve the cylinder of compression occurring at the ends of the stroke, substantially as set forth.
